(57) **CLAIM**

The ornamental design for cotton cleaning swab for animal ears, as shown and described.

DESCRIPTION

FIG. 1 is a perspective view of cotton cleaning swab for animal ears showing my new design;

FIG. 2 is a front/rear side elevation view thereof;

FIG. 3 is a left end elevation view thereof;

FIG. 4 is a right end elevation view thereof;

FIG. 5 is a top planar view thereof; and,

FIG. 6 is a bottom planar view thereof.

The broken line depiction of the hand in FIG. 1 has been shown for the purpose of illustrating environment that forms no part of the claimed design.

The broken lines encircling the base of the cotton cleaning swab for animal ears in FIGS. 1, 2, 5, and 6, are understood to represent stitching.

1 Claim, 2 Drawing Sheets

FIG. 3

FIG. 4

FIG. 5

FIG. 6
